UNITED STATES PATENT OFFICE.

BERNARD D. WILLIS, OF CHICAGO, ILLINOIS, ASSIGNOR TO AUTOMATIC ELECTRIC COMPANY, OF CHICAGO, ILLINOIS, A CORPORATION OF ILLINOIS.

SUBSTATION TELEPHONE-CIRCUITS.

1,313,570.

Specification of Letters Patent. Patented Aug. 19, 1919.

Application filed August 23, 1918. Serial No. 116,487

To all whom it may concern:

Be it known that I, BERNARD D. WILLIS, a citizen of the United States of America, and a resident of Chicago, county of Cook, and 5 State of Illinois, have invented certain new and useful Improvements in Substation Telephone-Circuits, of which the following is a specification.

My invention relates in general to substation 10 telephone circuits but is more particularly concerned with substation circuits for automatic telephone systems.

Briefly stated, the object of my invention is to provide a circuit arrangement whereby 15 there is introduced in a well known common battery substation circuit a subscriber's impulse sender, also old in the art, with a view to producing a more simple and efficient substation arrangement for automatic telephone 20 systems than has hitherto been available.

The preferred form of the invention has been illustrated in the drawing by means of two figures, of which Figure 1 is a detailed wiring diagram of an embodiment of the 25 invention which comprises a desk telephone set, while Fig. 2 is a diagrammatic showing of the fundamental principles involved.

Referring now to Fig. 2, the talking circuit is similar to the arrangement shown in 30 the patent to Scribner, #669,710, the transmitter T and a winding 4 of the induction coil I being in a bridge of the line conductors 2 and 3, while the receiver R in series with the condenser C and the other winding 35 5 of the induction coil I is connected in shunt of the transmitter. The above circuits of the transmitter and receiver are normally open and are closed when the receiver is removed from the receiver hook H. An 40 inspection of the figures will show that the transmitter bridge includes the switch hook controlled contact springs 6 and 7, while the receiver circuit includes the switch hook controlled contact springs 8 and 9.

45 A signaling bridge, comprising the ringer M and the previously mentioned condenser C, is provided as usual. It will be observed that this bridge is not under the control of the switch hook.

50 The subscriber's impulse sender or calling device, indicated by reference character S, may be of the type shown in the patent to Blessing #1,119,394. It comprises essentially a pair of impulse springs 14 and 15, 55 controlled by a cam (not shown) through the

medium of a finger hole dial (also not shown), and a pair of shunt springs 12 and 13 which are closed whenever the dial is turned from its normal position. The impulse springs 14 and 15 are included 60 in series with the line conductor 3 and their function is to produce momentary interruptions of the line circuit for the purpose of operating the central office switching devices. The shunt springs S, when closed, 65 short-circuit the signaling and talking circuit bridges in order to reduce the impedance and resistance of the line circuit, to prevent the interruptions being heard in the receiver, and to prevent tapping of the bell 70 during the transmission of impulses. It is to be noted that the connections of these shunt springs are such that if the calling device dial is operated when the receiver is on the hook the line will not be short-circuited. 75

In Fig. 1, a specific form of the circuit shown in Fig. 2 has been drawn in detail. The apparatus at the right of the drawing and comprising the transmitter T, the receiver R, the switch hook H, and the calling device S constitutes a desk set telephone; while the apparatus at the left of the drawing and comprising the ringer M, the condenser C and the induction coil I is separate from the said telephone and may be 85 mounted in the usual bell box. The telephone is provided with a terminal strip P in the base thereof and the bell box is provided with a terminal strip P'. The various circuits are completed by means of a five 90 conductor cord which connects the two terminal strips.

The advantageous arrangement of the various parts just described would not be possible without adding additional cord 95 conductors and other complications were it not for the new combination of circuits.

The operation of a substation instrument embodying my new circuits is as follows: When the receiver is removed to initiate a 100 call the switch hook controlled contact springs 6 and 8 come into engagement, respectively, with the contact springs 7 and 9, whereby the transmitter bridge and the receiver circuit are closed. Responsive to 105 the closure of the transmitter bridge current is supplied to the transmitter from a bridged battery at the central office (not shown) over the following path. Line conductor 2, winding 4 of the induction coil 110

I, transmitter T, switch hook springs 6 and 7, and calling device impulse springs 14 and 15 to line conductor 3. The bridge at the central office which includes the battery 5 may also, in accordance with the usual practice, include the controlling relay of an automatic switch, the circuit of such relay including, therefore, the transmitter bridge at the substation. It follows that the calling 10 subscriber may by suitably manipulating his calling device dial produce a series of interruptions in the circuit of the controlling relay to bring about the operation of the said switch. It is important to note 15 in this connection that as soon as the dial is turned from its normal position the substation loop is completed over a new path as follows: Line conductor 2, shunt springs 12 and 13, switch hook springs 6 and 7, and 20 impulse springs 14 and 15 to line conductor 3. By the closure of the above circuit the signaling and talking circuit bridges are short-circuited for the purposes previously mentioned. Successive operations of the 25 dial will now result in the operation of successive switches at the exchange, until the connection is finally completed to the line of the called subscriber, it being understood that all the switches are provided with controlling relay bridges which with the exception of the bridge in the last switch, are 30 successively cut off from the line when their associated switches are operated.

The connection being completed, conversation 35 may be held as desired. Since the operation of the talking circuits is well known it is not thought to be necessary to devote any space to the description of such operation herein. It may be mentioned, 40 however, that the ringer M which is bridged across the line during conversation, should be of very high impedance. When the receiver is replaced at the termination of the conversation the switch hook controlled contact 45 springs are separated to remove the transmitter from the line and to open the receiver circuit. It is necessary to open the circuit of the receiver in addition to that of the transmitter for otherwise the receiver together with the two windings of 50 the induction coil would form a shunt around the ringer M. The direct current loop at the substation being broken by the replacement of the receiver, current ceases 55 to flow over the line conductors and the switches at the central office are accordingly restored to normal in the usual and well known manner. The substation is now in condition to receive signaling currents 60 which may come in over the line conductors and traverse the ringer M and the condenser C, whereby the ringer is actuated to advise the subscriber of an incoming call.

It will be seen from the foregoing that 1 65 have devised new and simple circuits where-

by a common battery substation talking apparatus and a subscriber's impulse sender are combined without detracting from the talking qualities of the apparatus and without interfering with the efficient operation 70 of the impulse sender, thereby producing a highly desirable substation equipment for automatic telephone systems.

Having described my invention, what I consider to be new and desire to have protected by Letters Patent will be pointed out in the appended claims.

What I claim as my invention is:

1. In a substation telephone set, a line circuit, a bridge of said line including a transmitter, a second bridge of said line including a receiver, a third bridge of said line including a condenser, said first and second bridges normally open, means controlled by the switch hook for closing said normally open bridges, a calling device comprising a pair of impulse springs in series with one line conductor, and a single pair of shunt springs effective only when the receiver is removed to short-circuit all of 90 said bridges upon the operation of said calling device.

2. In a substation telephone set, a line circuit, bridges of said line including, respectively, a transmitter, a receiver, and a signaling device, switch hook controlled means for closing the first of said bridges, a subscriber's impulse transmitter for sending current impulses over the line circuit, a single pair of shunt springs in said impulse transmitter closed when the same is operated, and circuit connections such that if the receiver is off the hook, the closure of said shunt springs is effective to short-circuit the said transmitter, receiver, and signaling device, and such that if the receiver is on the hook, the closure of said shunt springs is effective to short-circuit said transmitter only.

3. In a substation telephone set, a line circuit; a transmitter and one winding of an induction coil in a bridge of said line, said bridge including contact springs for closing the same; a shunt circuit for said transmitter including a condenser, a second winding 110 of said induction coil, and a receiver; a set of contact springs in the shunt circuit between the receiver and the said second coil winding; a subscriber's impulse sender for transmitting current impulses over the line 115 circuit; and a single pair of shunt springs adapted to short-circuit the transmitter bridge when the said sender is operated.

4. In a substation telephone set, a line circuit, a ringer and a condenser in a bridge of 125 said line, a transmitter and a winding of an induction coil in a second bridge of said line, a receiver and a second winding of said induction coil connected in series to form a conducting path extending from the junc- 130

tion of the ringer and condenser to the junction of the transmitter and said first winding, a normally open connection in the transmitter bridge, a second normally open connection in said conducting path, means for closing said connections, a subscriber's impulse sender including make and break contacts for transmitting current impulses over the line circuit, and a single pair of shunt springs in said sender adapted to short-circuit the transmitter bridge when the said sender is operated.

5. In a substation telephone set, a line circuit, a transmitter in bridge of said line, a condenser, a winding of an induction coil, and a receiver in a second bridge of said line, a conductor common to said bridges and including a second winding of said induction coil, a normally open connection in each 55 bridge outside of the common conductor, means for closing said connections, a subscriber's impulse sender, and a single pair of shunt springs in said sender so connected that upon the operation of said sender both 60 the transmitter and receiver are shunted if the receiver is off the hook and the transmitter only if the receiver is on the hook.

6. In a substation telephone set, a line circuit, a transmitter in bridge of said line, a condenser, a winding of an induction coil, and a receiver in a second bridge of said line, a conductor common to said bridges and including a second winding of said induction coil, a normally open connection in each 65 bridge outside of the common conductor, means for closing said connections, a subscriber's impulse sender, a single pair of shunt springs in said sender so connected that upon the operation of said sender both 70 the transmitter and receiver are shunted if the receiver is off the hook and the transmitter only if the receiver is on the hook, a ter-

7. In a substation telephone set, a line circuit strip providing for the line connections and all connections of said condenser and induction coil, a second terminal strip 45 providing for all connections of the remaining apparatus, and a five conductor cord joining said terminal strips over which all necessary circuits are completed as set forth.

7. In a substation telephone set, a line circuit, a transmitter and one winding of an induction coil in a bridge of said line, said bridge including contact springs for closing the same, a shunt circuit for said transmitter including a condenser, a second winding 55 of said induction coil, and a receiver; and a set of contact springs in the shunt circuit between the receiver and the said second coil winding, a calling device comprising a pair of impulse springs in series with one line 60 conductor and a single pair of shunt springs effective only when the receiver is removed to short circuit all of said bridges upon the operation of said calling device.

8. In a telephone substation, a line circuit including a transmitter and one winding of an induction coil in bridge thereof, contacts for closing said bridge across the line, a shunt circuit for said transmitter including the second winding of said induction coil, a second set of contacts for closing said shunt circuit and a receiver and condenser included in said shunt circuit on opposite sides of the said second set of contacts, a calling device comprising a pair of impulse springs in series with one line conductor, and a single pair of shunt springs effective only when the receiver is removed to short circuit all of said bridges upon the operation of said calling device.

Signed by me at Chicago, Cook county, State of Illinois, this 9th day of August, 1916.

BERNARD D. WILLIS.
